SIDNEY H. HART, OF HOUSTON, TEXAS

COMBINATION PUNCHING AND EYELETING MACHINE

Application filed August 16, 1928. Serial No. 299,984.

My invention relates to a machine for perforating sheets and for upsetting or heading eyelets and similar members and while I have designed it more especially for closing seals on envelopes of the type shown in my co-pending application, Serial No. 299,983, filed Aug. 16, 1928, nevertheless the machine is not limited to that particular use.

The object of the invention is to provide a machine of very simple and inexpensive construction, having a perforating member for piercing a sheet or sheets and also a plunger for heading over or upsetting eyelets, both adapted to be operated by a single operating lever. Another object of the invention is to provide a machine of this character wherein the perforating member may be quickly thrown into or out of operative condition to permit either the perforating member or the riveting plunger to be operated. Another object is to provide a plunger operated by a lever wherein a revolving ball on top of the plunger is acted upon by the operating lever, so that the parts will operate smoothly and without friction notwithstanding any irregularities in the surface with which the ball member engages. Other advantages will be set forth in the following detailed description of my invention.

In the drawing forming part of this application,

Figure 1 is an elevation of a machine embodying my invention,

Figure 2 is a plan view thereof,

Figure 3 is an elevation of a portion of the machine corresponding with Figure 1, but showing the perforating member thrown out of operative condition,

Figure 4 is an elevation partly in section and showing the operation of the perforating and riveting members,

Figure 5 is an elevation showing the position of the parts at the time of the completion of the perforating operation,

Figure 6 is a sectional view taken on the line 6-6 of Figure 5,

Figure 7 is a perspective view with portions in section showing the assembly of the riveting plunger, and

Figure 8 is a perspective view of the parts of the perforating member.

The machine may have a frame constructed in various ways but herein I have shown a simple type of frame comprising a base 1 having an upwardly extending standard 2 extending partly horizontally in spaced relation to the base 1 and on its free end it carries a housing 3 in which the tools are mounted. At the upper and forward end of the housing 3 there is a rigid bracket 4 the upper end of which is bifurcated to form two parallel ears 5 having central apertures through which extends the stud 6. There is a hand lever 7 pivoted on the pin 6 and extending backwardly in line with and above the housing 3 the rear end 8 of this lever arm serving as a handle to be engaged by the hand to depress the lever and operate the tools hereinafter described.

I have shown the riveting tool arranged in advance of the perforating tool, although this relative location is not necessary to the employment of my invention.

I have shown a vertical bore 9 extending through the housing 3 and in the same vertical plane with the operating lever 7, and there is a plunger 10 which is adapted to reciprocate vertically in this bore. There is a coiled spring 11^a surrounding the upper end of the plunger 10 which projects above the housing 3 and this spring is adapted to be compressed between the top of the housing and a flange 11 projecting laterally from the plunger. This spring serves to retract the plunger to the elevated position shown in Figure 4 and it also serves to return the operating lever 7 into the position shown in the same view. The upper end of the plunger 10 is provided with a spherical socket 13 in which loosely seats a ball 14, the latter being held in place in the socket by the flange 15 which is slightly turned inwardly after the ball is in the socket 13, so that it engages the ball beyond its equatorial line to hold it in the socket but permit it to revolve freely therein in any direction. The top of this ball engages the curved surface 16 of the operating lever 7.

There is another bore 17 formed in the housing, which is also in line with the operat-

ing lever 7, and there is a tool 18 which is adapted to slide in this bore, the lower end of the tool being guided by a lining sleeve 19 at the bottom which is driven into the bore; and the tool itself is provided with a flange 20 projecting laterally therefrom and having a free sliding fit in the bore 17. There is a coiled spring 21 arranged to surround the tool 18 and to lie loosely in the bore 17 and this spring is adapted to be compressed between the flange 20 and between the nut 22 which is threaded into the enlarged upper end of the bore 17.

There is another spring 23, preferably stiffer in action than the spring 21, and this also surrounds the tool 18 and it is adapted to be compressed between the lining sleeve 19 at the bottom and between the flange 20 on the tool. There is pivoted by means of the pin 24 to the upper end of the tool 18 a rod 25 which is adapted to place the tool 18 either into or out of operative relation with the operating lever 7. The lower end of the plunger 10 is provided with a rounded projection 26 and a shoulder 27 which are adapted to co-operate with the hollow post of an eyelet for the purpose of upsetting the end of the eyelet as described in my said co-pending application. The lower end of the tool 18 is preferably chamfered, as shown at 28, to form the cutting edge, and this end of the tool is adapted to enter a perforation 29 in the base 1 as the tool passes through a sheet of paper or other material placed upon the base 1.

Assuming that the first operation to be performed is that of perforating one or more sheets of paper or other material to provide an aperture for an eyelet, the perforating tool will be placed in the operative condition shown in Figures 1, 4 and 5. This is done by turning the member 25 into a vertical position in line with the tool 18 and when the member 25 is in the vertical position the spring 21 presses on the flange 20 to hold the tool 18 depressed slightly, so that the pin 24 lies slightly below the nut 22 and while this condition exists the member 25 cannot move laterally because the portion 30 of the member 25 is prevented from swinging laterally within the housing.

If a sheet of paper or other material to be perforated is placed on the bed 1 and the lever 7 is depressed, it will press downwardly on the member 25 thereby moving the tool 18 downwardly until the lower end passes through the paper or other material into the aperture 29 of the base and in doing so the tool cuts an aperture in the paper or other material. The plunger 10 is also moved downwardly in this operation, but its lower end does not come into contact with the base 1 when the tool 18 is in its lowermost position, as shown in Figure 5, and therefore, the plunger 10 merely touches or presses on

the paper without performing any operation. When the handle 7 is released, the tool 18 is retracted by the spring 23 and the plunger 10 is retracted by the spring 11^a, the latter also serving to retract the lever 7.

After this perforating operation has been performed, an eyelet may be inserted through the perforation in the material whereupon the same is placed on the base 1 with the post of the eyelet directed upwardly and in line with the plunger 10. To avoid cutting a separate aperture in the material, the perforating tool is thrown out of operation. This may be done by lifting the member 25 and the tool 18 against the opposition of the spring 21 to raise the pin 24 and the end 30 of the member 25 out of the bore 17, whereupon the member 25 is turned on the pin 24 into the position shown in Figure 3. The end 30 of the member 25 will then rest on the nut 22 and will be held there by the downward pressure of the spring 21 so that the member 25 remains in the horizontal position shown in Figure 3. The plunger 10 may now be operated and the tool 18 will not be operated because the member 25 is no longer in operative relation with the lever 7.

As the handle 7 is depressed the plunger 10 is moved downwardly in opposition to the spring 11^a and the lower end of the plunger acts to turn over the upper end of the hollow post of the eyelet in similar manner to other types of eyeleting machines.

The ball 14 prevents any binding action between the lever 7 and the plunger 10 so that the device operates with a minimum of resistance even though the surface 16 is not perfectly machined. To return the perforating tool into active relation with the lever 7, the member 25 is swung upwardly into vertical position and when the end 30 swings into the bore 17 the tool 18 and the member 25 are slightly depressed by the spring 21 until overcome by the resistance of the upwardly acting spring 23. This will again move the end 30 and the pin 24 within the bore 17 to prevent lateral movement of the member 25. The tool will then be returned to the condition shown in Figure 4 and the perforating tool may be used as previously described.

Having described my invention, what I claim is:

1. A machine of the class described having a frame, a plurality of reciprocating tools, an operating lever for operating one or both of said tools, and means permitting a portion of one of said tools to be folded over with respect thereto to take it out of operation by said operating means.

2. A machine of the class described, comprising a frame, a plurality of adjacent tools adapted to reciprocate in said frame, and an operating member adapted to operate on both of said tools, one of said tools having a joint-

ed section adapted to be folded over to take said tool out of operative relation to said operating means.

3. A machine of the class described comprising a frame, a plurality of adjacent tools adapted to reciprocate in said frame, and an operating lever adapted to simultaneously operate both of said tools, one of said tools having a jointed section and adapted to be folded over to take said tool out of operative relation with said lever.

4. A machine of the class described including a frame, a plurality of tools arranged adjacent each other and adapted to reciprocate in said frame, springs for retracting said tools, and a lever adapted to simultaneously operate said tools in one direction, one of said tools including a pivoted member adapted to be folded over to take it out of operative relation with said lever.

5. A machine of the class described comprising a frame having guiding means, a tool reciprocating in said guiding means, a spring for actuating said tool, and means for reciprocating said tool in one direction, said tool having a pivoted member adapted to be folded over out of operative relation with said operating means, and when in operative position adapted to be held in alignment with said operating means by the tool guiding means.

6. A machine of the class described, comprising a frame provided with a bore, a tool reciprocating in said bore and having a spring for operating the tool, said tool having a jointed member adapted, when in alignment with said bore, to be guided against lateral movement, said tool being adapted to be lifted to disengage the joint from said bore to permit lateral swinging of said pivoted member, and an operating lever adapted to act on said pivoted member when in alignment with said tool.

7. A machine of the class described, comprising a frame having a bore, a tool reciprocating in said bore, a pivoted member on said tool, the pivot of which is adapted to be moved into said bore, oppositely acting springs operating on said tool and normally drawing said pivoted member into said bore when said pivoted member is in alignment with the bore, and a lever acting on said pivoted member for reciprocating said tool.

8. A machine of the class described, including a frame having a bore, a sleeve therein, a tool reciprocating in said sleeve and having a flange guided in said bore, springs acting on opposite sides of said flange in opposing directions, a nut forming a seat for one of said springs, a pivoted member connected with said tool and adapted to be normally drawn partly into said bore when in alignment with said tool and adapted to be lifted and to be turned laterally to hold said tool in retracted position, and an operating lever

adapted to operate on said pivoted member when the same is in alignment with the tool and to be inoperative when said pivoted member is swung laterally.

Signed at the city, county and State of ⁷⁰ New York, this 9th day of July, 1928.
